UNITED STATES PATENT OFFICE

JOHN F. SCHMIDT, OF CINCINNATI, OHIO, ASSIGNOR TO THE CORCORAN-BROWN LAMP COMPANY, OF CINCINNATI, OHIO, A CORPORATION OF OHIO

METHOD OF LAMP CONSTRUCTION

Application filed May 15, 1930. Serial No. 452,667.

The method of lamp construction I am about to describe has for an object to produce from a single piece of sheet metal, a lamp body and closure which, through the operations I am about to describe, will insure accuracy of sizes, ease of manufacture, reduction of costs, saving of material, and reduction in the number of manufacturing operations required to produce a lamp of the general type I have shown as exemplary of the invention I will now disclose.

In the drawings, Fig. 1 is a sectional elevation of the first step in the drawing of a lamp body and closure from a single piece of metal. Fig. 2 is a view similar to Fig. 1, but showing the second step which I take in preparing the body and closure for further manufacture.

Fig. 3 is a sectional elevation showing the third step which completes the formation of the body made in accordance with my invention.

Fig. 4 is a sectional elevation which shows the second step leading to the completion of a lamp closure for the lamp body shown in Fig. 3 and from the same blank from which the body was produced.

Fig. 5 is a view similar to Fig. 4, but showing a closure which has been completed from the partially completed closure shown in Fig. 4 by a third step in the method I will describe, ready for cooperation with the body shown in Fig. 6.

Fig. 6 is a sectional elevation disclosing an assembly of the elements shown in Figs. 3 and 5.

Previous to the step shown in Fig. 1, I cut a circular blank of sheet metal, which will be of sufficient diameter to permit of the formation of the shape shown in Fig. 1. This blank is then placed in a draw press and is drawn into the shape shown in Fig. 1. This constitutes the first step in my improved method and terminates with an edge 11 which is naturally somewhat uneven.

The second step is shown in Fig. 2 and consists in placing the first step form over or upon a die which has an annular groove in it at the point indicated by the cut line 12 and of the shape as would form the depre-

sion shape 13 in the metal of the cup shape when rolled or otherwise depressed therein. I accomplish the formation of this depression simultaneously with the operation of cutting the portion 14 from the body portion 15, the former portion being used for the closure rim, as will be explained. This cutting operation along the line 12, causes the metal of the cup to be depressed into the groove of the block or form upon which the cup is located for this operation, and is accomplished purposely in this manner so that each of the pieces thus resulting will have an inturned edge as at 16 and 17 on the closure piece 14 and body piece 15 respectively. Simultaneously with this cutting and shaping operation the forward uneven edge 11 of the closure piece is removed by a trimming operation along the line 18, which also reduces the closure piece to the proper width preparatory to completing the closure. With this second step completed, there are now two pieces completely shaped and trimmed to size ready for the separate handling and completion.

The third step now taken, and which completes the body, is shown in Fig. 3. This consists in merely rolling or otherwise shaping the edge of the body piece so that it is provided with an inturned wall 19 and a forwardly extending flange 20. The wall 19 forms a shoulder against which the closure is brought in assembling the lamp after completion, and the flange, which is preferably slightly tapered, receives and guides the closure into position on the body. In the forming of this wall and flange, the slightly inturned edge 17 performs the function of giving the metal of the body an easy start so that there is no chance of its splitting or tearing when forced into the shape shown in Fig. 3. Thus is the body completed, ready for such minor operations as making provisions for closure fastenings, connector mountings, lamp mountings, and the like.

I will now describe the operation of completing the closure. The first operation which consists in cutting off and trimming, and which has been described, also included the slight inturning of one edge of the clo-

sure. This, as in the case of edge 17, was done so that the ring of metal is stiffened, whereby a second operation, which I will now describe, could be carried out without the metal of the edge splitting or tearing. This second operation consists in completing the formation of the turned in edge 16. This is accomplished by rolling, spinning, pressing or otherwise forcing the partially turned edge 16 to become a reversed edge as at 21 in Fig. 4. Thus is a stiff, truly circular and smooth finished edge produced on the rear edge of the closure.

The third and final forming operation of the closure will now be described. This is illustrated in Fig. 5. Here, it will be found, that the forward true edge 22, which was produced by the cut 18, has been turned inwardly along a relatively wide roll formation 23 to produce a pleasing annular framing or rim around the closure glass with which the rim is supplied when the lamp is fully equipped. This roll is produced by rolling, pressing or otherwise causing the metal of the rim to be formed into the shape shown. The closure is now in condition for completion by providing it with the usual and suitable added feature by means of which it mounts the closure glass, and, in turn, is mounted on the lamp body which is shown in Fig. 3 and which has been described.

Reference is now made to Fig. 6, in which the body and closure are shown in cooperative relation, in order that the value of thus producing these two important elements of the lamp from a single piece of metal, may be appreciated, by disclosing the correct and accurate sizing of these parts for each other, as well as the fact that they have in this manner been made without great waste of material, such as is occasioned when the rim blank is cut from a separate disc of metal, thus necessitating the cutting out of a center disc of metal which has to be wasted for the most part even though smaller parts can be made from it. One point to which I draw attention is the fact that I purposely produce a slight inturning on but one edge of the closure annulus, as shown at 16 in Fig. 2, while the opposite edge 22, as shown in Fig. 4, is straight. This difference of initial formation is for specific purposes. In turning the rear edge 21, the shortness of the turn necessitates a preliminary "starting" of the metal in order that no buckling, tearing or cracking would occur in forming such a short inward turn, whereas, in turning such an edge as is shown in Fig. 5 at 23, the curvature in the die is of necessity so gradual that abruptness, such as at 21, is not present, hence enabling the metal to be rolled, pressed or otherwise formed into the shape 23 as shown. This preliminary inturning of the edge of the lamp body, as at 17, is also done

for the same purpose as that done on the closure, for the reason that the abruptness of the turns and shoulders adjacent to wall 19 of the body necessitates this preliminary "starting" operation.

Having thus described my invention, what I claim is:

A method of lamp construction consisting in forming from a sheet metal blank a cup of cylindrical wall shape, forming in the wall of the cup a circular depression at a predetermined distance from the edge, cutting through the depression at its greatest depth and thus leaving a partially turned edge on each of the severed portions, forming a shoulder on the partially turned edge of the remaining portion of the cup, forming a re-entrant flange on the partially turned edge of the ring-like severed portion, to fit the shoulder, and forming a flange on the remaining edge of the ring-like portion to mount a closure glass.

In testimony whereof I hereunto affix my signature.
